UNITED STATES PATENT OFFICE.

BENJAMIN PUTTERMAN, OF BROOKLYN, NEW YORK, ASSIGNOR TO AMERICAN AUTO LAMP CO., INC., A CORPORATION OF NEW YORK.

DESIGN FOR A VEHICLE SIGNAL LAMP.

Application filed August 13, 1924. Serial No. 10,444. Term of patent 14 years.

To all whom it may concern:

Be it known that I, BENJAMIN PUTTERMAN, a citizen of Poland, residing in the borough of Brooklyn, county of Kings, city and State of New York, have invented a new, original, and ornamental Design for Vehicle Signal Lamps, of which the following is a specification, reference being had to the accompanying drawings, forming a part thereof.

Fig. 1 is a front elevation of a vehicle sig-

nal lamp illustrating my improved design; Fig. 2 is a perspective view of a vehicle signal lamp, illustrating my improved design, without the support for said lamp.

I claim:

The ornamental design for a vehicle signal lamp, substantially as shown and described.

This specification signed this 29th day of July, 1924.

[L. S.] BENJAMIN PUTTERMAN.
